(57) **CLAIM**

The ornamental design for a jewelry setting, as shown and described.

DESCRIPTION

FIG. 1 is a perspective view of a jewelry setting, showing my new design;

FIG. 2 is a front view thereof;

FIG. 3 is a back view thereof;

FIG. 4 is a right side view thereof;

FIG. 5 is a left side view thereof;

FIG. 6 is a top plan view thereof;

FIG. 7 is a bottom view thereof; and,

FIG. 8 is another front view of the jewelry setting of FIG. 1, shown in a state of use.

The broken lines in FIG. 8 showing a gemstone represent environmental subject matter only and form no part of the claimed design.

1 Claim, 8 Drawing Sheets
